UNITED STATES PATENT OFFICE.

CORA M. KNAPP, OF CLEVELAND, OHIO.

WAFER-IRON.

No. 858,460.

Specification of Letters Patent.

Patented July 2, 1907.

Application filed December 3, 1906. Serial No. 346,045.

To all whom it may concern:

Be it known that I, CORA M. KNAPP, a citizen of the United States, residing at Cleveland, in the county of Cuyahoga and State of Ohio, have invented new and useful Improvements in Wafer-Irons, of which the following is a specification.

My invention relates to improvements in wafer-irons, and the primary object of the same is to produce a generally improved device of this class which will be exceedingly simple in construction, cheap of manufacture, and efficient in use, and which will be better adapted to its intended purposes than any other device of the same class with which I am acquainted.

Another object of the invention is to provide means whereby the mold or wafer-iron, proper, having the batter attached thereto, may be properly submerged in the hot lard, or other suitable material, in the vessel, while it is being cooked, without the necessity of manually holding it.

A further object of the invention is to provide a suitable and convenient means whereby the suspending shank may be readily attached to or disengaged from wafer-irons of varying configuration, and which may, at the same time, be conveniently handled without danger of burning the hand or hands of those using it.

With these ends in view, the invention consists in the novel construction, arrangement, and combination of parts, hereinafter described, illustrated in accompanying drawings, and particularly pointed out in the appended claims.

Referring to the accompanying drawings, Figure 1, is a side elevation, partly in section, of the wafer-iron. Fig. 2, a top plan view of the same. Fig. 3, an inverted top plan view of a bell-shaped wafer-iron. Fig. 4, a top plan view of a heart-shaped wafer-iron. Fig. 5, a transverse sectional view, taken through line "3-3", of Fig. 3.

Similar numerals of reference designate like parts throughout all the figures of the drawings.

Referring to the accompanying drawings 1, designates a wire, bent upon itself to form a loop 2, at its front end and then bent down to form a downwardly-extending shank 3, carrying at its lower end, in the present instance, a circular concavo-convex-shaped wafer-iron or mold 4, provided with a ferrule or hub portion 5, having a screw threaded opening adapted to screw on to a threaded portion of the lower end of the downwardly-extending shank 3. It will be observed that the wafer-iron or mold 4, is provided with

ribbed or corrugated walls 6. The rear portion of the wire 1, is provided with a wooden handle 7, and when it is desired to cook the batter clinging to the wafer-iron the same is properly positioned and submerged in hot lard, or other suitable material, by resting the wire 1, or handle portion, in a horizontal position over

the upper edges of the pot or vessel, the looped portion 2, taking over the opposite edge of the pot or vessel.

In Fig. 3, I have shown an inverted bell-shaped wafer-iron or mold provided at its base with a threaded opening 8, adapted to receive and take over the 60 threaded lower portion of the downwardly-extending shank 3, while in Fig. 4, I have shown a heart-shaped wafer-iron or mold consisting of two concentric heart-shaped bands 9, united and secured together by integral radially-extending arms 10, terminating at their 65 inner ends in a ferrule or hub portion 11, provided with a threaded opening 12, adapted to take over and be secured to the threaded lower portion of the downwardly-extending shank 3. It will be observed that the concentric bands or walls 13, of the bell-shaped 70 wafer-iron or mold, are tapered from top to bottom as shown most clearly in Fig. 5, for the purpose of permitting the wafer, when properly cooked, to be readily removed. The concentric walls or bands 9, of the heart-shaped wafer-iron or mold are similarly tapered 75 for the same purpose.

In practice the wafer-iron or mold is first dipped into the hot lard, or other suitable material, and thoroughly heated, after which it is dipped into a batter, the latter clinging to the sides or surfaces of the iron 80 and it is then placed in a pan or vessel of hot melted lard, or other suitable material, until the batter clinging to the iron is sufficiently cooked, whereupon it is removed and the cake allowed to fall or drop from the iron, on to a plate, or other proper receptacle. It will 85 of course be understood that in dipping the heated and greased iron into the batter care should be taken that it be not completely submerged, as in such instance the batter would cling to the upper surface of the iron and render it impossible to detach the cooked 90 cake therefrom without first scraping or cutting off the upper surface.

Having thus described my invention, without having attempted to set forth all the forms in which it may be made, or all the modes of its use, what I claim 95 and desire to secure by Letters Patent, is,—

1. A wafer-iron, consisting of two concentric bell-shaped tapered bands provided with a threaded portion and secured together at their top and base portions, and a handle or shank portion consisting of a wire bent upon itself to form a horizontally-extending loop at its front end in the same horizontal plane with the handle portion and then bent at the base of said loop to form a downwardly-extending shank having its lower end threaded and taking into said threaded portion. 100

2. A wafer-iron, consisting of a mold comprising two concentric tapered bands provided with a threaded opening, and a handle consisting of a wire bent upon itself to form a horizontal loop at its front end in the same horizontal plane with the handle and then bent at the rear of said loop to form a downwardly-extending shank having its end threaded to take into said threaded opening of the mold, said loop and handle being adapted to take over the 110

upper edges of the cooking-vessel to suspend the mold in proper position.

3. In a wafer-iron, the combination with a bell-shaped iron or mold provided at its base with a threaded opening; 5 of a handle consisting of a wire bent upon itself to form a horizontal loop at its front end in horizontal alinement with the rear or handle portion thereof and then bent to form a downwardly-extending shank at the rear of said loop having its end threaded to take into said threaded opening of said iron or mold.
- 10 4. In a wafer-iron, a handle consisting of a wire bent

upon itself to form a loop at its front end in horizontal alinement with the rear or handle portion thereof and then bent downwardly to form a suspending shank at right angles to said handle and loop.

In testimony whereof I have affixed my signature, in presence of two subscribing witnesses.
